UNITED STATES PATENT OFFICE.

MARThA HALoWEll CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A BOX COVER OR SIMILAR ARTICLE OF MANUFACTURE.

Application filed March 16, 1922. Serial No. 1,201. Term of patent 3½ years.

To all whom it may concern:

Be it known that I, MARThA HALoWEll CONNOR, a citizen of the United States, residing in the city of Baltimore, State of Maryland, have invented a new, original, and ornamental Design for a Box Cover or Similar Article of Manufacture, of which the following is a specification, reference being had to the accompanying drawing, forming a part thereof, wherein—

Figure 2 is a cross sectional view thereof. The design is shown as embodied in or applied to a box cover but I contemplate that the same may be also embodied in or applied to other analogous articles of manufacture.

What I claim is:

The ornamental design for a box cover or similar article of manufacture substantially as shown and described.

MARThA HALoWEll CONNOR.
